UNITED STATES PATENT OFFICE.

WILLIAM KOPP, OF DETROIT, MICHIGAN, ASSIGNOR TO JOSEPH N. SMITH & CO., OF DETROIT, MICHIGAN, A CORPORATION OF MICHIGAN.

MECHANICAL WINDOW LIFT.

Application filed April 26, 1918. Serial No. 230,366.

To all whom it may concern:

Be it known that I, WILLIAM KOPP, a citizen of the United States, residing at Detroit, county of Wayne, State of Michigan, have invented a certain new and useful Improvement in Mechanical Window Lifts, and declare the following to be a full, clear, and exact description of the same, such as will enable others skilled in the art to which it pertains to make and use the same, reference being had to the accompanying drawings, which form a part of this specification.

This invention relates to mechanical window lifts and a primary object of the invention is to provide a device for raising and lowering sash relative to a frame that may be readily and easily operated and automatically lock the sash in position. The device is particularly adapted for use with sashes housed between the side walls or panels of an automobile body or door and adapted to be raised relative thereto to close the vehicle and provide an open or closed panel in the body. Various novel features of the invention are involved in the means for raising the sash operable from the interior of the door or body of the vehicle and adapted to raise the sash and bring the same to position to engage over the lower rail of the window opening to provide a weather tight joint. An additional feature of the invention is involved in the means for operating the window whereby the sash may be partly raised and locked in any desired position either fully or partially closed or fully open. These general objects and the several novel features of the invention are herein-after more fully described and claimed and an embodiment of the invention is shown in the accompanying drawings in which—

Fig. 1 is an elevation showing my improved operating window lift and a part of a sash and frame therefor, the sash being partly raised.

Fig. 2 is a similar elevation from the opposite side, illustrating the position occupied by some of the parts when the sash is practically fully raised.

Fig. 3 is a sectional view showing the rail at the bottom of the sash opening and a section of the lower part of the sash and operating means therefor for drawing the same to place over the cross-bar or rail.

Fig. 4 is an elevation showing the gears

and sprocket for operating the sash and the lock employed to lock the gear with the sash raised at any predetermined height or position.

Fig. 5 is a cross section taken on line $x-x$ of Fig. 4.

Fig. 6 is a plan view of the handle used to operate the gears.

Fig. 7 is a cross section taken on line $y-y$ of Fig. 4.

Fig. 8 is an elevation of the part of the lower edge of the window sash showing the cam block utilized in operating the same to which the sprocket chain is attached and utilized in forcing the window up or down.

Fig. 9 is a cross section taken on line E—E 70 of Fig. 8.

Fig. 10 is a cross section taken on line F—F of Fig. 8.

Fig. 11 is an edge view of a chain link pivotally connected with the cam of Fig. 8 and 75 the lug for engaging the cam.

Fig. 12 is a plan view of the link.

Fig. 13 is an elevation showing the relationship of the chain links.

Fig. 14 is a side view thereof.

The apparatus for operating the window sash is mounted on a cross bar 1 of a window frame, the side member of which is shown at 2, and it is to be understood as being grooved to receive an edge of the sash as shown by dotted lines at the right of Fig. 1. The apparatus is mounted on a plate 3 secured to the cross bar 1 in any approved manner, and this plate has rotatably mounted thereon a combined sprocket and gear wheel 4. The gear teeth are of the usual spur gear type and the sprocket is formed by the studs or pins 5 equidistantly positioned in a circle on the inner face of the gear wheel. This gear and sprocket wheel 4 is driven by a gear 6 mounted on the same side of the plate 3 as will be understood from Fig. 5. The gear 6 is provided with a hub riding in an aperture provided in the said plate 3 and has attached thereto a plate 7 spaced from the hub by the side flanges 7^a and held by means of screws 8. This plate 7 has a central aperture 9 which aperture has a pair of oppositely disposed lugs 10 projecting thereinto for a purpose hereinafter mentioned. Between the plate 7 and the hub of the gear 6 is positioned a pair of locking bars 11 and 12. These bars are each substantially

80

85

90

95

100

105

U

shaped in form and are positioned in reverse relation with the leg of one inserted between the legs of the other as shown particularly in Fig. 4. Each outer leg of both the bars 5 11 and 12 is provided with a tooth 13, which normally projects into spaces 14 between a circularly arranged series of lugs 15 formed on or secured to the plate 3 as will be understood from Fig. 4. A U shaped spring 16 is 10 interposed between the outer leg of one U and the inner leg of the other in both instances tending to move the bars outwardly with the teeth or lugs 13 engaging between the said circularly arranged lugs 15, and 15 this movement forces the inner legs of the bars to adjacent relation although spaced apart as shown providing a narrow elongated slot centrally in alignment with the aperture 9 in the plate 7. To guide the bars 20 in their movement the plate 7, which is to be understood as being removed from the face of the said bars in the Fig. 4, may be provided with side flanges 7^a, shown in Fig. 7 and indicated by dotted lines in Fig. 4, 25 which serve to prevent displacement of the bars. The bars 11 and 12 and plate 7 therefore are preferably provided with a cover plate 19 as will be understood from Fig. 5 which may be secured to the plate 3 in any 30 desired manner.

The gear 6, it will thus be understood is normally held in locked position by reason of the introduction of the lugs or teeth 13 on the bars 11 and 12 respectively between 35 the lugs 15 on the plate 3 preventing rotation thereof and the purpose of this will be described hereinafter. To rotate the gear, a handle 20 is provided preferably rotatably mounted in a plate 21 adapted to be secured 40 to the cover plate 19 holding the end 22 of the handle in position extending through a central aperture 23 in the cover plate 19 and through the aperture 9 in the plate 7 and between the adjacent faces of the inner legs 45 of the U bars 11 and 12. The end 22 of the lever or handle 20 is sufficiently narrow in width to be introduced between the ends of the bars and is of a length nearly equal to the diameter of the aperture 9 in the plate 50 7. When the handle is in position with the end inserted as stated, by turning the handle and rotating the end 22 thereof the two inner legs of the U bars are forced apart against the tension of the springs 16. This 55 withdraws the teeth 13 from between the lugs 15 and continued movement of the handle brings opposite ends of the part 22 thereof into engagement with the opposite lugs 10 projecting into the aperture 9 on the 60 plate 7 which contact enables the handle to rotate the plate carrying with it the gear 6 by reason of its connection therewith. On release of the handle after desired rotation of the gear 6 the springs 16 automatically 65 force the tongues or teeth 13 between the

lugs 15 and locks the gear in any of the various possible positions and in the event that the lugs 13 should engage against the face of a lug 15, slight pressure on the gear 4 would tend to rotate the gear 6 until the 70 teeth 13 were disposed opposite the opening between the lugs 15 whereupon the gear 6 would be locked thus locking the gear 4 from rotation. The gear 4 on the inner face thereof has a chain one end of which is 75 pivotally attached at 30 to the gear and the other end of which is pivotally attached to a block 31 carried by the window sash as will be understood from Fig. 1. Each of these links, except the link pivoted at 30 to the gear, is provided with a notch 32 to one side of the pivot point of the links as will be seen in Fig. 13. These notches are undercut as shown and the pins 5 on the gear are 80 preferably provided with a head to allow these notched portions of the link to engage therebeneath as will be understood from Fig. 1. The links are thus supported on the pins after the manner of a sprocket. The links further are provided at the said notched end 85 with a lug 33 which engages in a notch 34 on the opposite end of the attached link. By this type of joint the links may be turned on the pivots in one direction and that is toward the notched side 32 and, when 90 brought to alignment in the manner shown in Fig. 13 and in the lower part of Fig. 1, the chain becomes sufficiently rigid at the joints to prevent further turning thereof, in a direction reverse to that in which they turn 95 about the sprocket. It is to be understood that the links of the chain when in the position shown in the lower part of Fig. 1 are not exactly in straight line as is indicated but that the lugs 33 are so positioned as to 100 allow the joints to be turned slightly more than 180 degrees and thus are slightly to the right of a straight line from the pitch line of the gear to the point in engagement with the block. Thus, with pressure applied 105 by rotation of the wheel to force the sash downward the said pressure tends to turn the links to still greater angle but, by reason of being prevented by the lug, sufficient rigidity is secured to cause the desired movement of the sash by operation of the gear wheel. Buckling of the chain to the left from the position in Fig. 2 is thus prevented. The lug 33 and notch 34 are so positioned 110 to allow the links to turn backward slightly beyond a vertical relationship whereby pressure exerted on the end of the chain tends to turn the links backward relative one to the other. This being limited by the lug 33, force may be applied at the end of the chain 115 and the sash moved downward in its frame by reason of the connection of the lower end of the chain with the block 31 carried by the sash. By this arrangement an endless chain is not required there being only a 120 125 130

chain of sufficient length to reach from the sash at its lowermost position to the sprocket.

The block 31 rides in a way provided between the lower sash bar 50 and a bar 51 secured thereto. The lower end link 32^a of the chain is shown in detail in Figs. 11 and 12 from which it may be seen that the link is provided with a trunnion 52 adapted to fit in an aperture 53 in the block, a detail of which is shown in Figs. 8, 9 and 10. This block is notched as indicated at 54, the notch opening into the central aperture as shown and opens through the upper edge of the block and through the left side thereof as shown in Fig. 8 at which point one wall of the notch is beveled as shown at 55 providing a cam face. The end link 32^a adjacent the trunnion 52 is provided with a lug 56. With the trunnion 52 in place in the aperture 53 of the block 31 and the link in vertical position as shown in Fig. 1, the lug 56 occupies the upper vertical part 54 of the notch therein and is out of contact with the walls of the notch. The lower side of the lug is provided with an angular face 57 shown more particularly in Fig. 3, and when the link is turned to horizontal position, which is the position occupied thereby when the chain has been turned about the sprocket to bring the end link to the position shown in Fig. 2, the angular face of the lug is brought in contact with the face 55 of the block. It is to be noted that on rotation of the gear 4 and winding the chain on the sprocket provided on the gear, the sash is raised in the frame by reason of the connection of the chain with the said block 31. As the chain reaches its uppermost position as shown in Fig. 2 (in which the gear and links are shown by dotted lines in position thereon and the block 56 in full lines relative to the cam face of the block 31) the block rides longitudinally in the way provided and is thus carried by the link to the left to the position shown in Fig. 2 to bring the end link in horizontal position with the lug 57 in engagement with the angular face 55 of the block. When the block has reached the position shown in Fig. 2 the window has been raised to its full extent, slightly above the cross rail 90 of the window frame as shown in Fig. 3. A continued movement from the position shown in Fig. 2 causes the lug 57 to engage the cam 55 and the chain being held in position on the wheel therefor forces the lug downward against the cam face 55 and moves the lower end of the sash in the direction shown by the arrow in Fig. 3 so that the lip 60 carried by the outer face of the sash is brought over the weather strip 61 on the rail 90, thus making a weather tight joint. It is to be noted that, as the block 31 is moved to the left by this final rotation of the gear that as the pivotal

point of the link 32 reaches the highest point vertically above the center of the gear, the highest position of the sash is attained as shown in Fig. 3. If the gear be rotated further, the sash will be moved downward 70 inasmuch as the said pivotal point of the link 32 begins to travel downward with the gear from this high point. Therefore as the block passes the high point, the end of the sash is moved first outward over the 75 weather strip 61 and then downward into engagement with the strip 61 by reason of the engagement of the lug with the cam. On reverse direction of rotation of the gear and chain thereon, the first movement of the sash is upward by reason of the pivotal point of the chain and block moving upward around the gear toward the highest point and as it passes the highest point the sash is then moved downward as the block 80 passes downward around the gear. As the link passes from the gear, it is continued to be forced downward by reason of rotation of the gear and operation of the chain heretofore described, and the force applied to 85 the links forces the sash downward as will be understood from Fig. 1.

The normal position of the sash 50 relative to the bar 90 is shown in full lines in Fig. 3 in which position the sash is vertical. 90 The groove in the window frame for the said sash 60 is to be understood as being of such form, however, as to allow the lower end of the sash to be moved to the position shown by dotted lines in Fig. 3 with the member 100 60 engaging over the weather strip 61, the cam arrangement above described being of a character to force the lower end of the sash out of its normal position. On reversing the operation as above described to raise 105 the sash from engagement with the strip 61, the sash will naturally return to the position shown by full lines in Fig. 3 when the cam members are out of contact due to the tendency of the sash to swing inward to 110 normal vertical position in the groove therefor.

If the sash has been moved part way downward by rotation of the gears shown through rotation of the handle, release of 115 the handle at any point will allow the teeth 13 on the bars 11 and 12 to be extended into the notches between the teeth 15 which holds the gear 6, and consequently the gear 4 in mesh therewith, from rotation. By this arrangement the sash may be locked in any intermediate position as may be desired. This is of value in that it is frequently desirable to have a window of a closed type of automobile body partly open and in such rigid position as not to be accidentally displaced. 120

It is preferable that a spiral spring 70 be provided to act as a counterweight for the sash. This spring is shown in Figs. 1 and 130

4 and should preferably be positioned between the gear 4 and the supporting plate with one end attached to the gear and the other end to the plate.

5 From the foregoing description it is evident that the device is simple in construction and very easily operated, and that the sash is forcibly moved either upward or downward as may be desired and is locked 10 in any position and may be moved in either direction from the locking position by rotation of the operating handle in the desired direction.

Having thus briefly described my invention what I claim is—

1. In a mechanical window lift the combination with a frame and sash slidable therein, of a sprocket, a chain connected therewith and with the sash in such manner 20 that rotation of the sprocket in one direction or the other causes upward or downward movement of the sash in the frame, a gear for driving the sprocket, a plate fixedly supported in spaced relation with the gear and having a central aperture, a pair of spring-actuated locking bars supported between the plate and the gear, means engaged by the bars when released to action by the springs preventing rotation of the gear, and a handle 30 device for rotating the gear, said handle device being adapted upon turning thereof to first withdraw the locking bars from locking position and upon release of the handle to release the bars to return to locking position 35 by action of their springs.

2. In a mechanical window lift the combination with a frame and window sash slidably mounted therein, said frame having a cross bar and the sash having a bar adapted 40 to seat over said cross bar, of a rotatable element supported by the frame, a block secured to and slidably longitudinally of the lower sash bar, a chain having one end connected with the rotatable means and the 45 opposite end connected to the block, rotation of the said element raising or lowering the sash in the frame by means of the chain, and means carried by the chain and engaging the block adapted to force the sash laterally 50 when in the uppermost position over the said cross bar and thence downward into weather tight engagement therewith.

3. In a mechanical window lift, the combination with a frame and sash slidable 55 therein, said frame having a cross bar, of a block carried at the lower edge of the sash and movable longitudinally thereof, a sprocket rotatably supported by the frame, a chain having one end pivotally attached to 60 the sprocket and the other end pivotally connected with the block said block having a cam face, the end of the chain connected with the block being provided with a lug adapted to engage the said cam face when in horizontal relation with the block and to with-

draw from engagement with the cam face when in vertical relation with the block, means for rotating the sprocket to raise or lower the sash, the links of the chain being pivotally connected to turn in one direction 70 and to a limited extent in the opposite direction whereby force applied to the links when free from the sprocket forces the sash downward, an upwardly projecting strip carried by the lower cross bar of the window opening, and a complementary strip carried by the lower bar of the sash adapted to engage over the strip on the cross bar, the engagement of the link with the cam face of the block when the sash is raised to its uppermost position forcing the sash laterally over the cross bar and continued movement of the sprocket and consequent movement of the block in its way drawing the window downward with the complementary strip engaging over the projecting strip on the cross bar.

4. In a mechanical window lift, a sprocket, a chain connected therewith and to the sash in such manner that rotation of the sprocket 90 in one direction raises the sash and in the opposite direction lowers the sash, a gear for driving the said sprocket, a plate apertured to support the gear, a plate fixedly supported in spaced relation with the gear and having a central aperture, lugs projecting inwardly from opposite sides of the aperture toward the center thereof, a pair of locking bars supported in position between the plate and the gear, said bars each having terminal lugs 95 or teeth, the supporting plate for the gear being provided with circumferentially positioned spaced lugs between which the teeth of the bars are adapted to engage, an operating device for the said gear having means thereon extending through the aperture of the said plate and between the locking bars, the arrangement being such that on operation of the said operating device the teeth of the bars are first withdrawn from between the lugs of the plate whereupon the internally projecting lugs of the central aperture are engaged by said means and the gear rotated, springs adapted to force the bars to locking position, the release of the said operating means allowing the springs to force the teeth of the bars into engagement between the lugs.

5. In a mechanical window lift in combination with a frame and window sash slidably mounted therein, of a sprocket rotatably mounted on the frame, a block at the lower end of the sash mounted to slide parallel with the plane of the sash, a chain having one end attached to the sprocket and the other end pivotally connected with the block, the links of the chain being pivoted together in a manner to allow the turning thereof about the sprocket and further being provided with means limiting the relative turning of 130

the links in the opposite direction whereby the chain may act as a bar to force the sash downward on rotation of the sprocket, said block having a cam face and the link 5 pivotally connected with the said block having a lug adapted to engage the cam face as the link is turned on its pivot, said block, cam and lug as the end link rides over the sprocket at the completion of the upward

movement of the sash, cooperating to first 10 force the sash outward and then downward, a cross bar for the frame and a corresponding bar on the sash adapted to engage over the cross bar of the frame when forced outward and downward.

In testimony whereof, I sign this specification.

WILLIAM KOPP.
